FIG. 1

FIG. 2

FIG. 3

FIG. 4

FIG. 5

FIGURE 1 is a front elevational view of an electronic computer showing my new design;

FIGURE 2 is a rear elevational view thereof;

FIGURE 3 is a top plan view thereof;

FIGURE 4 is a left-side elevational view thereof; and

FIGURE 5 is a perspective view of the front of the computer, the rear thereof being broken away for convenience of illustration.

The dominant features of my design resides in the combination, on the computer disclosed, of asymmetrically delineated rectangular panel areas wherein control knobs and information displays are disposed substantially along vertical and horizontal axes, all recessed within the peripheral casing border, as shown.

I claim:

The ornamental design for an electronic computer, as shown and described.
